UNITED STATES PATENT OFFICE.

CHARLES WIRT, OF CHICAGO, ILLINOIS.

DESIGN FOR AN INSULATOR-BRACKET.

SPECIFICATION forming part of Design No. 21,455, dated April 12, 1892.

Application filed October 23, 1891. Serial No. 409,626. Term of patent 3½ years.

To all whom it may concern:

Be it known that I, CHARLES WIRT, a citizen of the United States, residing at Chicago, in the county of Cook and State of Illinois, have invented and produced a new and original Design for Brackets for Electric Wires, of which the following is a specification.

My design relates to brackets, and of it the following is a specification, reference being had to the accompanying drawings, forming part thereof.

Figure 1 is a side view of my bracket. Fig. 2 is a plan view of the same.

Like parts are indicated by the same letter in both figures.

A is a standard, hollow to receive a shaft, or it may form part of the supporting-shaft. B B are arms projecting therefrom and pro-

vided each with a central vertical rib and two horizontal plates C C above and below the rib. 20

D D are cylindrical pieces, hollow to receive insulator-stands, or solid and continuous, with screw-threaded insulator-stands E E.

F is a cylindrical portion, either of a greater 25 or less diameter or the same diameter as the part A, having the same axis and extending between the plates C C.

I claim—

The design for an electrical insulator-bracket, substantially as herein shown and described. 30

CHARLES WIRT.

In presence of—

CELESTE P. CHAPMAN,
ANNA COBURN.
